(57) **CLAIM**

The ornamental design for a table having a padded bumper, as shown and described.

DESCRIPTION

FIG. 1 is a front elevation view of a table having a padded bumper showing my new design, the opposite side being a mirror image of the shown;

FIG. 2 is a right elevation view thereof, the opposite side being a mirror image of the shown;

FIG. 3 is a top plan view thereof;

FIG. 4 is a bottom plan view thereof; and,

FIG. 5 is an isometric view thereof.

The broken lines on the corners of the table top depict stitching.
